UNITED STATES PATENT OFFICE.

GEORGE A. HOFFMANN, OF BLOOMFIELD, NEW JERSEY.

FINGER SLIP.

Application filed April 29, 1925. Serial No. 26,726.

The purpose of the invention is to provide a device for application to the fingers of an infant to effect a permanent cure of the habit where there is a tendency or inclination on 5 the part of the subject to suck the fingers.

With this purpose in view, the invention consists in a construction and combination of parts of which a preferred embodiment is illustrated in the accompanying drawings, 10 wherein:

Figure 1 is a perspective view of the invention.

Figures 2 and 3 are respectively vertical and transverse sectional views on the planes indicated by the lines 2—2 and 3—3 of 15 Figure 1.

Unlike devices of this general character, the present invention is not designed to preclude the subject placing the finger in the 20 mouth but to make the operation obnoxious so that he is finally broken of the habit. The device comprises a finger stall 1 and wrist-band 2 connected as by a web-portion 3. The web portion finger stall and wrist-band are integrally connected and of reticulated structure, being preferably of open 25 crochet construction. It is, therefore, washable and hence sanitary. The open stitch exposes the fingers, preventing the drawing 30 of the fingers through as a result of perspiration.

The absorbent quality of the thread of which the device is constructed is adapted for holding a harmless medicated solution 35 for a period of time—and such a solution may be used in connection with the invention to create a disagreeable taste in the mouth of the subject. The device, being of soft material, cannot injure the face or eyes 40 when the hand is rubbed across the face, and the open and rough stitch creates an unpleasant feeling within the mouth without

harming the latter or the gums and thus does not cause any discomfort. With all, the subject has the free use of the hands 45 without any annoyance.

Being constructed as shown, it is applicable to either hand and to a particular finger of the hand on which it is applied, and being capable of material stretching because of the open-work construction, may be used on different subjects whose hands differ in size within a reasonable range. The device is made preferably of linen thread, but obviously may be constructed of cord, cotton, silk, wool or any other material found suitable. 55

The wrist-band 2 at one extremity is provided with a button 4 constituting a detachable connection for the application and 60 removal of the device, the button being inserted through a selected mesh opening.

Although designed primarily as a means for curing the finger sucking habit, the invention is susceptible of use for other purposes. For example, it may be employed 65 as a sanitary finger covering to hold gauze or cotton to the fingers of children or adults when dressing cuts, bruises or burns.

The invention having been described, what 70 is claimed as new and useful is:

A device for the purpose indicated comprising a finger stall, a wrist band, and a web portion connecting the wrist band with the stall, the whole being of integral construction and reticulated structure and the wrist band having a button at its free extremity selectively engageable with openings in the reticulated structure to hold the band 75 in attached surrounding relation to the wrist 80 of a wearer.

In testimony whereof he affixes his signature.

GEORGE A. HOFFMANN.
